UNITED STATES PATENT OFFICE

2,506,184

RECESSED GAME BOARD AND PLAYING
PIECES THEREFOR

Millicent C. Twining, Cape May, N. J.

Application April 21, 1947, Serial No. 742,943

5 Claims. (Cl. 273—135)

1

The object of the invention is to provide an improved game, that is especially designed for and takes into consideration the psychology of young children in their characteristic tendency to visualize and materialize their imaginative family and home-building creations, though the game is by no means limited to very young children, and in addition may be used with smaller children as a toy and to teach words from objects.

Another object is to provide in such a game a move-indicating means, such as a spinner or the like, having spaces characterized by pictorial representations of the elements that comprise an average family and comfortable home, as for example a father, mother, sister, brother, maid, one or more pets, house, garage, automobile and others, as may be desired.

A further object is to provide an improved spinner, that can be used in playing the game, comprising a card or other surface bearing circumferentially arranged spaces separated by preferably radially extending boundary lines between such spaces, and a spinner element having a single pointed arm extending in one direction, while its oppositely extending arm is branched to provide a plurality of relatively pointed terminals, so that if the single pointed end stops upon a dividing line between two adjacent spaces, the oppositely directed subdivided terminals will point to two (or more) spaces, thereby insuring a player a chance to move or to place one or more player pieces regardless of the position of the single pointed end.

Still another object is to provide in such a game an object, such as a house, garage, etc., that is subdivided into two or more vertically related parts, as for example the foundation, the body, the roof and perhaps the chimney of the house, but in any case a relationship of the parts of the article in question, such that the lowermost or foundation section must be "played" and positioned first before the body, roof and chimney (if present) can be assembled upon said foundation in their proper sequence.

A still further object is to provide in such a combination aligned, polygonal apertures extending through the house sections and of such cross section as to receive the chimney piece when extending therethrough, in order to properly align and prevent relative lateral movement or dis-

2

placement of one section with respect to one or more of the other sections.

And a still further object is to provide a playing board, having recesses to determine the positions of and receive at least some of the playing elements, such as house and garage foundations, and aligned sections of fence.

With the objects thus generally stated, the invention comprises further details of construction and method of play, such as are hereinafter fully brought out in the following description, when read in conjunction with the accompanying drawings, in which Fig. 1 is a plan view of a playing board for use in the new game; Fig. 2 is a section on the line A—A of Fig. 1; Fig. 3 is a perspective view of the four sections of a house element such as is used in the game, the several sections of which are shown in slightly spaced relation; Fig. 4 is a similar view of the house when assembled; Figs. 5 and 6 are perspective views that correspond with Figs. 3 and 4, but instead represent the sections of a garage both in separated and assembled relationship; Fig. 7 is a plan view of a spinner such as is used in the game; Fig. 8 is a side elevation of the same; Fig. 9 is a fragmentary plan view of a slightly modified form of spinner; Fig. 10 is a player piece representing the father; Fig. 11, the mother; Fig. 12, the sister; Fig. 13, the brother; Fig. 14, the family cat; Fig. 15, the pet dog; Fig. 16, a bush or shrub; Fig. 17, a flag and its staff; Fig. 18, a tree; Fig. 19, an automobile; Fig. 20, a gate-containing section of fence; Fig. 21, an uninterrupted or uniform fence section; Fig. 22, the maid; Fig. 23, the little baby sister; Fig. 24, a dog kennel; Fig. 25, a second automobile, the player pieces of Figs. 22 to 25 being termed bonus pieces; and Fig. 26, which is a side elevation of a modified form of the house element, partly in section to show how in this modified form the chimney element extends vertically through the roof, body and foundation sections thereof, to connect the same together and prevent their accidental separation or lateral displacement.

45 In explaining the new game, a description of the player pieces and other objects used will first be given. Each player is given a playing board that comprises a flat board 1 of convenient size, and so printed, lithographed or otherwise decorated and shaped, as to provide recesses or de-

pressions 2 and 3 adapted to receive and positively position house and garage pieces, respectively, while a narrow groove 4 extends about and slightly within the periphery of the edge of said board, to receive player pieces which together represent fence.

The house (Figs. 3 and 4) is preferably composed of a base section 5, a body section 6 and a roof section 7, while the roof section is provided with a recess 8 in which a chimney piece is adapted to be inserted. The base section is intended to be played and placed in the recess 2 which it snugly fits, after which the body, roof and chimney sections are played in sequence and placed in the relative positions shown in Fig. 4. A modified form of house assembly is shown in Fig. 26, and comprises base, body and roof sections 5', 6' and 7', respectively, said sections in this case being provided with vertically aligned apertures, which when assembled cooperate to form a channel 8', through which a single elongated chimney piece 9' is inserted, after which this chimney piece operates to detachably secure the three first-mentioned sections together in alignment, as shown.

The garage is composed of a body section 10 that is first played and placed in the recess or depression 3 before its roof section 11 can be played and placed upon it, as indicated in Fig. 6. Gate-containing and plain sections of fence 12 and 13 are shown in Figs. 20 and 21, and these when played are placed in the groove 4, with the gate section in substantial alignment with the outer end portion of a walk and drive area 14, the arrangement of the house and garage depressions and of said walk and drive being in accordance with the preferences of the manufacturer.

One of the outstanding advantages of this new game is that fact that it can be played by very young children, once they have been taught the simple basic fundamentals. This is illustrated by that fact that the move-indicating element (Figs. 7 and 8) comprises a plane base 15 of any desired shape upon which a spinner 16 is pivotally mounted, said spinner carrying the customary two oppositely directed pointed ends 17 and 18, while said base is also provided with circumferentially positioned sectors 19, in which are reproduced the pictorial representations of the objects that are also represented by the respective player pieces.

Thus, while each of said sectors contains the properly spelled name of a player piece, for older children who are able to read, the pictorial representation of the particular piece is also included, so that the young child learns to read the proper piece to play by its corresponding picture in the space to which one of the pointed ends 17 and 18 points. For example, the young child does not have to be able to read the words "flag," "father," "mother," etc., but upon seeing the pictures of the respective objects plays the player piece resembling the corresponding object.

The modified form of spinner shown in Fig. 9 comprises a pivotally mounted element 16' having a single pointed end 17' and in the opposite direction a double or subdivided pointed end 18'-18'', so that instead of a player being unable to play when the pointed construction of Fig. 7 stops upon a dividing line, he will still be able to elect between the pieces indicated by the double ends 18'-18'' when the end 17' stops upon such a line. In this manner, if desired, a disappointment of the child player in not being able to play when the ends 17 or 17' rest upon a dividing line, might be

turned into an advantage by permitting him to play both of the pieces indicated by the double points thus provided.

The player pieces represented by Figs. 10 to 19 inclusive are intended to be played in accordance with any predetermined set of rules, and in accordance with the indications made by the spinner, these player pieces being in addition to the house, garage and fence pieces first above referred to. The pieces shown in Figs. 22 to 25 are so-called bonus pieces and are played as they are won by the persons playing. While any desired set of rules may be used, a simple form of playing is as follows:

In a game of the particular construction, size and number of pieces here illustrated, before starting the game each player is given a playing board, nine pieces of fence and one each of the player pieces (Figs. 3, 5, and 10 to 19). The bonus pieces (Figs. 22 to 25) are placed to one side. One of the players starts to the game and the others take their turns in any predetermined order, each spinning the spinner and placing player pieces upon his board as indicated by the positions at which the spinner element comes to rest, using one or both of the single spinner points, or all of them in the case of the form shown in Fig. 9 being used, or of the double pointed end, if the single pointed end stops upon a dividing line, as previously explained, all depending upon the rules adopted.

If the base of the house is played, it is placed in the recess or depression 2, but if the body or the roof is indicated first, it cannot be played until the one or more lower sections have been played and properly positioned. The same holds true for the garage. Each player in his turn may either play only once, or may continue to play until unable to play any of his pieces, before surrendering the spinner to the next player. It will be noted that in each sector is the word (or a representation) of "fence." A piece of fence is not played as long as the object in the same space can be played, but is resorted to when the pictorially represented objects have already been played, or when for example the house or garage body section can not be played, due to their base sections not having been played.

As to the bonus pieces indicated by the drawings, the first player to complete the house automatically gets the maid (Fig. 22); the first to complete his garage gets the bonus car (Fig. 25); the first player to get the dog and the cat upon his board gets the doghouse (Fig. 24); and the first player to get the entire family of father, mother, sister and brother automatically gets the baby sister (Fig. 23) as a bonus piece. Of course, any such arrangement of rules is purely arbitrary, as many variations in the rules may be made while using the same construction of player pieces, spinner illustrations with or without the double-ended spinner, etc., wherefore the invention is not limited to the rules above set forth, as the foregoing is to be considered only as illustrating the use of the novel player pieces, illustrated spinner and the like.

Having thus described my invention, what I claim and desire to protect by Letters Patent of the United States is:

1. In a game apparatus in which positioning of game pieces depends upon operation of a spinner or chance device, the apparatus comprising a board, a plurality of objects in separable sections constituting said game pieces, means on said board separably interfitting with a coacting game piece

of one object, means on said board dissimilar to the first mentioned means separably interfitting with a coacting game piece of another object, whereby each of said coacting game pieces will interfit with one only of said means.

2. Game apparatus comprising a board having dissimilar first and second recesses, dissimilar game pieces interfitted in said recesses respectively, and game pieces respectively differing in shape and size from the first mentioned game pieces separably superposed thereon and coacting therewith to represent different objects.

3. Game apparatus according to claim 2 wherein in the two uppermost game pieces of one object are separably interfitted.

4. Game apparatus according to claim 2 wherein a game piece extends above the lowermost game piece of one object and through and above the remainder of the game pieces of the latter object.

5. Game apparatus according to claim 2 wherein in said recesses are separated from each other, and means delineated on the board between the recesses representing a path connecting said objects.

MILICENT C. TWINING.
